MACHINE FOR FINE GRADING

Stephen A. Scullen, Cohoes, N. Y.

Application February 21, 1930, Serial No. 430,297

7 Claims. (Cl. 37—108)

My invention relates to road grading machinery and particularly to a machine for milling the subgrade of a concrete pavement to a precise grade or elevation preparatory to laying the 5 pavement thereon; this application being a continuation in part of my application Serial No. 293,010, filed July 16, 1928.

In the preparation of the subgrade for a concrete pavement it is extremely important to the 10 contractor that it be brought to the precise grade and cross-section required by the plans. The plans and specification for such pavements always prescribe a certain minimum thickness of concrete, the upper surface of which must be 15 laid to a precise grade or elevation, but it is of little moment to the State, municipal corporation or other employing party if the contractor lays a pavement which is thicker than the prescribed minimum. However, on account of the 20 high cost of materials going into a pavement of this character, any increase in thickness over the prescribed minimum is a source of great loss to the contractor.

It is therefore customary to rough grade the 25 subgrade, set the side forms to precise grade, and then fine grade the subgrade between the forms and ahead of the mixer by hand. Grading in this way, by hand labor, is not only very slow and very expensive by reason of the direct cost of 30 doing it, but is also very costly to the contractor where the finished subgrade is even as little as a quarter or a half inch lower than that absolutely necessary to provide the prescribed minimum thickness of concrete. On a 30 foot road, for 35 example, if the subgrade averages one-quarter of an inch too low the excess concrete required per mile is about 122 cu. yds. and, if the subgrade is one-half an inch too low the extra concrete yardage is, of course, double this. It is 40 very difficult, even with the most careful workmen, to fine grade the subgrade to the precise elevation required, and in all cases where the operations of the contractor are closely supervised by an engineer or inspector the subgrade 45 is low.

The principal object, therefore, of my invention is to provide a means for fine grading the subgrade of a concrete road or the like so that it will be brought to the precise grade required 50 to give the minimum slab thickness prescribed. Another object is to provide a machine which will perform its work quickly and cheaply and in which the material removed will be deposited outside of the forms. Another object is to provide 55 a machine of this character which will pre-

pare a subgrade of any desired transverse cross-section, that is, bank the subgrade on curves, or cut the subgrade to any required crown.

With these objects in view my invention includes the novel elements and the combinations 60 and arrangements thereof described below and illustrated in the accompanying drawings, in which—

Fig. 1 is a plan view of my machine;

Fig. 2 is a side view thereof;

Fig. 3 is a fragmentary detail of a cutter for 65 crowning the subgrade; and

Fig. 4 is a detail elevation view of the conveyor reversing mechanism.

Generally speaking, my machine comprises a 70 mechanism supporting frame which is mounted on flanged wheels adapted to ride upon the side forms as rails. The element which performs the fine grading is a comparatively small diameter high speed milling cutter which extends transversely across the subgrade between the forms, and which turns in such a direction as to throw the cut material ahead of itself and away from the finished grade. The milling cutter, on account of its high rotative speed, and on account 75 of the slow rate at which it is automatically fed into the material to be cut reduces this material to a very fine dust which is projected ahead of the cutter upon a conveyor extending transversely of the machine and adapted to dump the 80 material outside of either side of the form.

Referring to the drawings for a more particular description of my machine, 1 is a frame of angle irons or other suitable structural shapes forming 85 a general support for the mechanism. This frame is mounted upon axle, 2, at the rear of the machine and axle, 3, at the front, and these axles carry the flanged wheels, 4, adapted to ride on the side forms, 5. Supported upon the frame, 1, is an internal combustion engine, 6, which serves, 90 not only to move the machine along the side forms and thus feed the cutter into the work but also serves as a source of power for driving the cutter and the conveyor. The manner in which the engine, 6, is connected to the axle shaft, 2, and to the 95 cutter bar and conveyor is not important although it is desirable that the drive be positive and the gearing be such that the cutter bar is turned at about 800 R. P. M. and that it be fed into the material to be removed at a rate of only 3 or 4 100 feet a minute.

In the drawings, I have shown a sprocket wheel, 7, mounted upon the engine shaft. This sprocket drives the transverse shaft, 8, mounted in suitable bearings on frame, 1, by means of the chain, 110

9. Mounted upon the shaft, 8, is the small sprocket, 10, driving chain, 11, running over a large sprocket wheel, 12, mounted on transverse shaft, 13, near the rear of the machine. The transverse shaft, 13, is mounted in suitable bearings on the frame, 1, and has loosely mounted thereon the bevel pinions, 14 and 15, both of which are in mesh with a larger, master gear, 16, mounted on shaft, 17. Clutches, 18 and 19, are provided in connection with the bevel pinions, 14 and 15, through the medium of which either pinion, 14, or pinion, 15, may be positively connected to the shaft, 13, and be driven thereby. The clutches, 18 and 19, are operated together by means of the handle, 20, so that when pinion, 14, is connected to shaft, 13, pinion, 15, is disconnected and vice versa. This provides the necessary mechanism for reversing the movement of the machine along the side rails.

21. At 21, I have shown a speed reducing mechanism which may, for example, be in the ratio of 200 to 1. That is, if the shaft, 17, turns 200 revolutions per minute the shaft, 2, which drives the rear wheels, 4, will turn only once a minute. 22. Whatever gearing arrangement is used between the engine, 6, and the rear driving wheels, 4, the ratio should be such that when the engine is running at normal speed the machine will be moved along the rails at a comparatively low rate of speed, say 3 or 4 feet per minute.

23. There is also mounted upon shaft, 8, a sprocket, 22, driving chain, 23, running over a sprocket, 24, on the shaft of the milling cutter, 44. The ratio of the gearing here should be such that when the engine is running at normal speed and the entire machine is being driven along the rails at 3 or 4 feet per minute the cutter will be turned at comparatively high speed, say about 300 R. P. M.

24. This milling cutter is of comparatively small diameter and preferably, but not necessarily, comprises a square bar, about 4 inches on the side, which is mounted in suitable bearings on the frame, 1, and extends transversely across the machine practically to the inside of the forms on each side. In any event the cutter bar obviously should extend just as close to the inside of the forms as is possible. Mounted upon this square bar are the slightly spaced knives, 25, forming substantially continuous cutting edges extending transversely across the subgrade. These cutting edges are preferably made up of a plurality of separate units or knives each secured to the bar by means of bolts or cap screws, 26, and having the rear edge of each unit abutting against the side of an element on an adjacent side of the square bar. The free ends of these elements extend a short distance only beyond the shaft on which they are mounted, and preferably a distance which is less than the diameter of the shaft itself, in order that the elements may withstand the severe usage to which they are subjected. These separate elements which go to make up the cutting edge are quite closely spaced as shown in Fig. 1, and the separate elements on the different sides of the shaft may be staggered as shown. There are two reasons why the cutting edges are preferably formed in this way. One of these reasons is because if one of the smaller elements is broken or nicked it may be readily replaced without replacing the entire cutting edge extending across the machine. Another reason is because it permits different lengths of cutting elements to be applied at different parts of the milling cutter so that the device may be

adapted to cut a crowned or other specified subgrade.

The bearings at each end of the milling cutter and in which it is supported may be raised or lowered independently of each other by means of suitable adjusting devices, 27, so that the cutting element may plane the subgrade to a transverse slope where required.

Just in front of the cutter is a conveyor, represented generally by the numeral, 28, which extends transversely of the machine and somewhat beyond the side forms as shown in Fig. 1. This conveyor preferably consists merely of a horizontal plate, 29, supported from the frame, 1, at an elevation just above the top of the side forms and across which are dragged a plurality of bars or scrapers, 30, connected to the chains, 31. These chains extend over sprockets, 32 and 33, at one side of the machine and the sprockets, 34 and 35, at the other end of the machine. Sprockets, 34 and 35, are connected to shaft, 36, mounted in bearings, 37, on frame, 1, and sprockets, 32 and 33, are connected to shaft, 38, supported in bearings, 39, secured to the frame.

It is desirable that the conveyor should be reversible so that material may be carried to either side of the road bed. Loosely mounted on shaft, 38, are two bevel pinions, 45 and 46, both of which are in mesh with bevel gear, 47, on vertical shaft, 48. The shaft, 48, at the upper end, 105 has mounted thereon a bevel pinion, 49, which meshes with pinion, 50, on shaft, 51, extending transversely across the frame and which is driven by sprocket wheel, 52, and chain, 53, running over sprocket, 54, on driven shaft, 13. The pinions, 45 and 46, are provided with clutches, 55 and 56, respectively, which operate in substantially the same way as clutches, 18 and 19, on shaft, 13. These clutches are actuated together by lever, 57, (see Fig. 1). When lever, 57, is 115 pushed in one direction, pinion, 45, for example, is secured to shaft, 38, through the clutch mechanism, 55, and pinion, 46, is disengaged from shaft, 38, by means of clutch mechanism, 56. When the lever, 57, is pushed in the reverse direction, pinion, 46, is secured to shaft, 38, by means of clutch mechanism, 56, and pinion, 45, is disengaged. Thus, the conveyor may be driven in either direction.

In operation, my machine is mounted upon the side forms as shown in the drawings and is disposed ahead of the mixer which is laying the concrete. It is propelled slowly along the forms (at 3 or 4 feet per minute) and the milling cutter is adjusted to cut the subgrade to the precise elevation by means of the elevation regulating devices, 27. The milling cutter revolves very rapidly (around 300 R. P. M.) in the direction of the arrow shown in Fig. 2. On account of this comparatively high rotative speed the material 120 of the subgrade with which it is slowly brought into contact is reduced to a comparatively fine dust which is projected forwardly, upwardly and away from the milling cutter. To prevent the material from being thrown upwardly and to insure its being projected forwardly upon the conveyor, I provide over the milling cutter, a suitable hood or deflector, 40, as shown in Fig. 2. The side of the conveyor adjacent the milling cutter is provided with an apron, 41, which is hinged 125 to the conveyor plate, 29, at 42. The lower edge of this apron, 41, or dust pan drags along on the subgrade and forms an inclined surface up and over which the material is thrown by the milling cutter onto the conveyor. Suitable 130

means, 43, may be provided for raising the apron or dust pan and securing it in raised position when it is desired to move the machine backwardly.

From the foregoing it will be apparent that I have provided a device which will precisely plane the subgrade of a concrete road far more accurately, more quickly and cheaper than it can be done by hand. I consider it quite essential that the cutting element be of comparatively small diameter and that it be rotated at comparatively high speed. In other words, my cutting element does not function as a digging element or as a scarifying element, but functions very much like a milling cutter on a milling machine. It is quite essential too that the cutter rotate in the direction shown, that is, in such a direction that it will throw the material ahead thus leaving the subgrade over which the milling cutter has already passed in perfect condition.

While I have described my invention in its preferred embodiment it is to be understood that the drawings are merely illustrative, that the words which I have used are words of description rather than of limitation, and that changes, within the purview of the appended claims, may be made without departing from the true scope and spirit of my invention in its broader aspects.

What I claim is:

1. In a machine for milling to precise elevation the surface of the subgrade for a pavement, a wheeled frame, a rectangular cutter shaft thereon, means for independently adjusting the respective ends of the cutter shaft with respect to the frame, a plurality of cutting blades secured in spaced relation on each side of the shaft, the blades on one side being offset longitudinally of the shaft with respect to the blades on the adjacent side and bridging the space between the blades on such adjacent side, the cutting edges of the blades extending beyond the periphery of the shaft at one end and the heel end of the blades on one side abutting squarely against the surface of the blades on the adjacent side.

2. In a machine for milling to precise elevation the surface of the subgrade for a pavement, a wheeled frame, a rectangular cutter shaft thereon, means for independently adjusting the respective ends of the cutter shaft with respect to the frame, a plurality of cutting blades secured in spaced relation on each side of the shaft, the blades on one side being offset longitudinally of the shaft with respect to the blades on the adjacent side and bridging the space between the blades on such adjacent side, the cutting edges of the blades extending beyond the periphery of the shaft at one end, the heel end of each blade abutting squarely against two blades on the adjacent side of the shaft, means for operating the shaft in a direction to cause the cutting action of the blades to exert a lifting influence on the material cut, and means car-

ried by the frame to receive the raised material for delivery beyond the road-bed.

3. A machine for milling to precise elevation the surface of the subgrade for a pavement comprising a frame, wheels carrying said frame and adapted to roll on the side forms for said pavement, means for propelling said device at a comparatively slow rate of speed, a milling cutter of comparatively small over all diameter extending transversely of said frame but comprising a shaft of comparatively large size having a plurality of peripherally spaced cutting edges thereon projecting but a comparatively small distance from the exterior of said shaft whereby said milling cutter and the cutting edges thereof are endowed with great strength and resistance to flexure, means for raising and lowering each end of said cutter independently of the other, and means for rotating said cutter at a high speed adapted to impart thereto a velocity of attack on outcroppings of rock and the like sufficient to fracture and pulverize the same.

4. A machine for milling to precise elevation the surface of the subgrade for a pavement comprising a frame, wheels carrying said frame and adapted to roll on the side forms for said pavement, means for propelling said device at a comparatively slow rate of speed, a milling cutter of comparatively small over all diameter extending transversely of said frame but comprising a shaft of comparatively large size having a plurality of peripherally spaced cutting edges thereon projecting but a comparatively small distance from the exterior of said shaft whereby said milling cutter and the cutting edges thereof are endowed with great strength and resistance to flexure, means for raising and lowering each end of said cutter independently of the other, and means for rotating said cutter at a high speed adapted to impart thereto a velocity of attack on outcroppings of rock and the like sufficient to fracture, pulverize and project the cut particles thereof forwardly in the direction in which the machine is moving, and a movable conveyor extending transversely of said machine in front of said milling cutter arranged to catch the particles projected from said cutter.

5. The structure set forth in claim 3 in which the speed at which the milling cutter is driven is in excess of 600 R. P. M.

6. The structure set forth in claim 4 in which the speed at which the milling cutter is driven is in excess of 600 R. P. M.

7. The structure set forth in claim 3 in which the peripherally spaced cutting edges comprise a multiplicity of separate but closely spaced elements arranged in rows extending longitudinally of the cutter; said elements being removably secured to said shaft whereby nicked or broken elements of the cutting edges may be readily replaced.

STEPHEN A. SCULLEN.
